UNITED STATES PATENT OFFICE.

LOID E. WHITNEY, OF HERMOSA, SOUTH DAKOTA.

DOOR FASTENER.

Application filed March 7, 1925. Serial No. 13,866.

This invention appertains to closure operators and fasteners and the primary object of the invention is the provision of a novel means for facilitating the easy operation of a sliding door and novel securing means cooperating with the operating means for holding the door in a closed position against operation by an unauthorized person.

10 Another object of the invention is the provision of a sliding closure operator embodying a sliding operating bar carried by the closure having means for permitting the operation thereof from the interior and exterior of the closure, a swinging operating lever operatively connected with the closure and closure frame and a novel securing latch bar pivotally associated with the closure and adapted to be moved into the path of the 20 operating lever when the closure is in its closed position so as to effectively prevent the operation thereof.

A further object of the invention is the provision of novel means for permitting the 25 connection of the latching lever with the operating lever, whereby the latch lever will be firmly held in place against swinging movement.

A still further object of the invention is 30 to provide an improved device of the above character, which will be durable and efficient in use, one that will be simple and easy to manufacture and one which can be placed upon the market and incorporated with a 35 sliding closure at a small cost.

With these and other objects in view, the invention consists in the novel construction, arrangement and formation of parts, as will be hereinafter more specifically described, 40 claimed and illustrated in the accompanying drawings, in which drawings:

Figure 1 is a side elevation of the sliding closure operator and the novel securing means therefor, the closure being shown in 45 its closed position in full lines and in its open position in dotted lines.

Figure 2 is a fragmentary perspective view of the sliding closure operating means and the securing or latching lever thereof, the 50 operating means being in closed position,

Figure 3 is an elevation of the operating means showing the latch lever in its securing position, the guide pins of the operating lever being shown in section,

55 Figure 4 is a detail horizontal section taken on the line 4-4 of Figure 1.

Figure 5 is a detail section taken on the line 5-5 of Figure 3.

Referring to the drawing in detail, where-in similar reference characters designate like or corresponding parts throughout the several views, the letter A generally indicates the sliding closure which can be considered as a door in the present instance. The door A is mounted in suitable tracks 60 (not shown) in the door frame B, which as shown embodies the longitudinally extending sill 10.

Associated with the door A and the frame B is the novel door operating means C and 70 the novel securing device D for the operating means C, which forms the important part of the present invention. The door operating means C comprises a sliding operating bar 15 which is mounted for movement in a 75 horizontal plane over the face of the door in suitable guide brackets 16 secured to the door. The outer end of the operating bar 15 at the opposite faces thereof is provided with the manipulating handles 17 and the innermost handle is extended through a suitable slot 18 formed in the door A. By this construction, it can be seen that the operating bar 15 can be readily actuated both from the inside and outside of the door. The inner end of the operating bar is offset as at 80 19 and provided with an inwardly extending manipulating pin 20 which is mounted in a longitudinally extending slot 21 formed in the actuating lever 22. The actuating lever 22 is rockably mounted at its lower end 85 upon a suitable pivot pin or shaft 23 carried by the sill 10 and this lever extends upwardly toward the operating bar 15. The extreme upper end of the actuating lever 22 is provided with an eye or staple 24, 90 for a purpose, which will be hereinafter more fully described. Mounted within the guide slot 21 of the lever 22 is a headed guide pin 25 rigidly carried by the door A. If so desired the upper end of the slot 21 95 can terminate in an angularly extending section or pocket 26 in which the guide pin is adapted to fit when the door is in its extreme closed position.

By operating the bar 15, the lever 22 can be swung on its pivot 23, which will slide the door A in its track, either to its open or closed position depending upon the direction the bar 15 is moved.

The novel means D employed for holding the door in its closed position and the op-

erating means C against movement embodies the swinging latch lever 30, which is pivoted at its upper end as at 31 to the door A. As shown the pivot point of the latch lever 30 is located above the upper end of the actuating lever 22 and at one side thereof. When the actuating lever is swung to move the door to closed position, the latch lever 30 is permitted to ride under the upper end 10 of the frame, and the latch lever is provided with an offset bracket 32 for engaging the outer face of the lever. This bracket 32 carries an eye or staple 33, which is adapted to aline with the eye or staple 24 carried by 15 the actuating lever, when the door is closed. A suitable padlock may be engaged through the alined eyes 24 and 33 so as to prevent manipulation of the latch lever 30 by unauthorized persons. Due to the abutting relation 20 of the eyes 24 and 33 swinging movement of the lever 22 is prevented and consequently the door will be held against movement. The latch lever 30 may be disposed at substantially right angles to the actuating lever 22, when the same is in locked position so that any movement of the lever 22 will be transmitted directly to the pivot pin 31.

Changes in details may be made without 30 departing from the spirit or scope of this invention but what I claim is:

1. A fastener for a sliding closure including guides arranged in a horizontal plane carried by the closure, an operating bar slidably mounted in said guides, manipulating handles for the operating bar, a rockably mounted lever having a longitudinally extending slot therein, a guide pin carried by the closure mounted in said slot, and an 35 operating pin rigidly carried by the operating bar slidably mounted in the slot.

2. A fastener for a sliding closure includ-

ing a pivoted actuating lever, a member movable into and out of the path of the lever for holding the same against actuation, 45 and an operating bar slidably carried by the closure and having a slidable connection with said actuating lever.

3. A fastener for a sliding closure including a swinging lever, a latch member movable into and out of the path of said lever, eyes carried respectively by the lever and latch member adapted to aline when the latch member is moved in the path of the lever, a lock adapted to be associated with 50 said eyes, and an operating bar carried by the closure and having a slidable connection with said swinging lever.

4. A fastener for a sliding closure including an operating bar slidably mounted upon the closure in a horizontal plane, a rockably mounted lever having a longitudinally extending slot therein, a guide pin carried by the closure mounted in said slot, and an operating pin carried by the operating bar 55 slidably mounted in the slot.

5. A fastener for a sliding closure including an operating bar slidably mounted upon the closure in a horizontal plane, a rockably mounted lever having a longitudinally extending slot therein, a guide pin carried by the closure mounted in said slot, an operating pin carried by the operating bar slidably mounted in the slot, a latch member 60 movable into and out of the path of said lever for holding the same and the closure against movement, eyes carried respectively by the lever and latch member adapted to aline when the latch member is moved in the path of the lever, and locking means 65 adapted to be detachably associated with said eyes.

In testimony whereof I affix my signature.
LOID E. WHITNEY.
